DESIGN FOR BARBECUE TONGS

Frederick K. Storm, Los Angeles, Calif., assignor
to Adel Precision Products Corp., a corporation
of California

Application November 19, 1945, Serial No. 123,856

Term of patent 3½ years

(Cl. D44—29)

To all whom it may concern:

Be it known that I, Frederick K. Storm, a citizen of the United States and residing at Los Angeles, in the county of Los Angeles, State of California, have invented a new, original, and ornamental Design for Barbecue Tongs, of which the following is a specification, reference being had to the accompanying drawing, forming part thereof, in which:

Fig. 1 is a top plan view of barbecue tongs showing my new design;

Fig. 2 is a side elevation of said tongs; and

Fig. 3 is an end elevation of said tongs looking toward the free ends thereof.

I claim:

The ornamental design for barbecue tongs, substantially as shown.

FREDERICK K. STORM.
